UNITED STATES PATENT OFFICE

165,246

FAN BLADE

Joseph T. Roffy, Huntington Park, Calif.

Application October 23, 1950, Serial No. 12,688

Term of patent 14 years

(Cl. D26—7)

To all whom it may concern:

Be it known that I, Joseph T. Roffy, a citizen of the United States, residing at Huntington Park, county of Los Angeles, State of California, have invented a new, original, and ornamental Design for a Fan Blade, of which the following is a specification, reference being had to the accompanying drawing, forming a part hereof.

Fig. 1 is a plan view of a fan blade, showing my new design.

Fig. 2 is a side elevational view.

Fig. 3 is an end view.

I claim:

The ornamental design for a fan blade, substantially as shown.

JOSEPH T. ROFFY.
